UNITED STATES PATENT OFFICE.

AMOS C. WOLLENHAUPT, OF SAN ANTONIO, TEXAS.

CHICKEN ROOST.

Application filed February 18, 1927. Serial No. 169,290.

This invention relates to a sanitary and sectional roost for chickens.

An object of the invention is the provision of a device adapted to be employed as a roost in a chicken house and in which a roost is formed of removable sections so that any number of the sections may be employed as may be required relative to the length of the house.

A further object of the invention is the provision of a simple, compact and sectionally constructed roost in which all the parts are formed of a material which may be readily cleaned and which may be readily removed, said roost also providing a support for a plurality of readily removable nests supported in a protected manner by an extensive dropping board.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a view in perspective of a roost constructed in accordance with the principles of my invention,

Figure 2 is a transverse vertical section, and

Figure 3 is a view in perspective of a removable nest adapted to be associated with the roost.

Referring more particularly to the drawings 10 and 11 designate a pair of legs for supporting one end of the roost while 12 and 13 represent legs for supporting the opposite ends of the roost and which extend sufficiently above the dropping board 14 for carrying a division plate 15 secured at its opposite ends to a flange of the legs 12 and 13. The legs it will be noted are formed of angle irons which provide for a ready securing of the various elements to the legs. The legs are connected together by angle irons 16 which form the longitudinal supports of the board 14. Diagonally disposed brace bars 18 connect the flanges of the legs with the depending flange of the angle bars 16. Transverse bars 19 brace the lower ends of

the legs at the opposite ends of the roost. The legs are also braced above the board 14 by means of transverse rail supporting bars 20.

A plurality of rails 21 formed of any suitable material such as wood and impregnated with a solution to prevent film from nesting on said bars are provided with metal hooks 22 at their ends to engage over the transverse bars 20, supporting the opposite ends of the rails. By this construction the rails may be readily removed when desired.

A pair of rails 23 are provided at the ends with hooks 24 adapted to engage over the top of the transverse bars 19 and provide supports for nests, generally designated by the numeral 25. The end walls 26 of the nest are extended upwardly or an additional plate or sheet of metal is secured to the inner face of the end walls and is bent outwardly in a horizontal position, as shown at 27, and depending flanges 28. The flanges 27 are adapted to engage over the bars 23 and the flanges 28 aid in maintaining the bars in spaced relation and also to prevent the bars from slipping out from under the horizontal flanges 27. The bottom 29 of the nest is perforated, as shown at 30, to permit the circulation of air. The upper ends of the side walls 31 of the nest are rolled into the form of an elongated eye, as shown at 32, to receive a wire for bracing the upper edges of said nest.

Side boards 33 are adapted to be placed longitudinally of the roost and with the lower ends in engagement with the outer longitudinal edges of the board 14 in order to prevent any material on the board from being discharged on the floor of the house. These boards are removable and for this purpose the plates 34 are secured to the opposite ends of the board and are offset at their outer ends so that the inner end 35 of the side board 33 may engage the inner face of the flanges of the legs while the cleats 34 engage the outer face of the flanges so that the side boards may be removed by elevating them sufficient to clear the top edges of the post. The ends of the side boards 33 terminate short of the pair of the side flanges of the legs so that they will clear the brace bar 20 and the division plate 15. The upper ends of the side boards 33 are rolled to provide a sleeve 42 for the reception of a reinforcing rod 43.

From the above description it will be noted that the rails 21 forming the roost for the chickens and the pairs of rails 23 forming a support for the nests may be readily removed as are the side boards 33. The dropping board may be made of metal and formed in sections if desired. The ends and side edges of the board rest respectively on the bars 17 and the longitudinal bars 16.

10 Where the board 14 is made of metal it may be corrugated in order to provide for additional strength and the ends, as shown at 40, are rolled to provide elongated eyes to receive reinforcing wires.

15 I claim:—

1. A roost comprising a supporting frame including legs and flanged connecting bars, certain of the flanges of the connecting bars being located in a horizontal plane, a dropping board having its edges resting upon the adjacent flanges of the connecting bars, brace bars connecting the legs at the ends of the frame, and rails removably connected with the brace bars, and nests removably supported on the frame below the dropping board.

2. A roost comprising a supporting frame including legs and flanged connecting bars, certain of the flanges of the connecting bars being located in a horizontal plane, a dropping board having its edges resting upon the adjacent flanges of the connecting bars, brace bars connecting the legs at the ends of the frame, rails removably connected with the brace bars, side boards located along the longitudinal edges of the dropping board and having removable connections with the

legs whereby said side boards are readily removed from the frame, and nests supported on the frame and in protected relation by the dropping board.

3. A roost comprising a supporting frame including legs and flanged connecting bars, certain of the flanges of the connecting bars being located in a horizontal plane, a dropping board having its edges resting upon the adjacent flanges of the connecting bars, brace bars connecting the legs at the ends of the frame, rails removably connected with the brace bars, a second pair of brace bars connected with the legs at the ends of the frame, rails removably supported by the last-mentioned brace bars, and nests removably supported by the last-mentioned rails.

4. A roost comprising a supporting frame including legs and flanged connecting bars, certain of the flanges of the connecting bars being located in a horizontal plane, a dropping board having its edges resting upon the adjacent flanges of the connecting bars, brace bars connecting the legs at the ends of the frame, rails removably connected with the brace bars, a second pair of brace bars connected with the legs at the ends of the frame, rails removably supported by the last-mentioned brace bar, nests removably supported by the last-mentioned rails, said nests having a perforated bottom and side walls provided with extensions adapted to engage over the last-mentioned supporting rails.

AMOS CHAS. WOLLENHAUPT.
